UNITED STATES PATENT OFFICE

2,542,875

FEED STRUCTURE FOR TUBE MILLS

Anderson MacPhee, Chesterfield, England, assignor to Mitchell Engineering Limited, London, England, a British company

Application June 10, 1946, Serial No. 675,713
In Great Britain July 3, 1945

2 Claims. (Cl. 241—171)

1

This invention relates to ball tube mills such as are used for grinding coal, limestone and other materials which are to be reduced to a finely powdered form. It is the object of the invention to improve the construction of such mills, the means of supporting and driving them, and of delivering the materials to be ground thereto.

In a well known type of ball tube mill the material to be ground is introduced through a hollow trunnion, generally with the use of an Archimedean screw feed, and there are journal, ball or roller bearings disposed around the hollow trunnion. This arrangement is not altogether satisfactory in use, and one of the features of the present invention is a construction which eliminates the necessity for a hollow trunnion. Other features are concerned with the charging apparatus, a spider through which the material is admitted, and devices for avoiding the accumulation of material at the entry to the mill.

The invention is illustrated by way of example in the accompanying drawings, in which:

Figure 1 is a side elevation partly in section of a ball mill constructed according to the invention;

Figure 2 is a detail view of an enlarged scale of a part of the shaft end seen in Figure 1;

Figure 3 is an elevation of the lifters on the drum supporting spider at the feeding end; and

Figure 4 is an elevation of the feeding hopper and throat fillers, Figures 3 and 4 looking in opposite directions along the axis of the supporting shaft.

The body of the mill consists of a tube or cylinder 10, generally of steel, which may be of any convenient length, say 9 or 10 feet long, and any suitable diameter such as 4 feet, 6 inches. The mill has a lining of hard steel plates 11, which are renewable as they wear, preferably supported on a layer of resilient material 12 which may be cork, India rubber or the like. The middle portion of the cylinder is broken away in the drawings, but will generally embody a removable door or manhole with a bolted flange giving access to the interior for renewing the lining and so forth. The cylinder has flanges 13 secured to it at its ends to which are bolted castings 14 and 15 at the two ends. Each of these castings has a coned flange portion expanding outwardly toward the interior of the cylinder and a spider consisting in this case of four spokes 16 connecting the coned flange to a hub 17 by which the castings 14 and 15 are respectively mounted on the end of the shaft 18

2

at the driving end, and a stub shaft 19 at the other end. A suitable cross section for the arms 16 is indicated in Figure 1 by showing a portion of the horizontal forwardly projecting arm in section in front of the hub 17.

A suitable feeder delivers the material to be ground to a hopper 20, whence it falls down a chute 21 with a steeply inclined rear wall leading down to a casting 22 forming a filler between the bottom of the chute and the aperture of the spider in the end casting 14, through which the material to be ground enters the mill. The members 23 are inserted at a substantial angle with respect to the horizontal axis of the shaft and are adapted to deflect material around said shaft and toward the spaces between the arms of the spider. The shaft itself is surrounded by inserted members consisting of castings 23 and 24 above and below which enclose the shaft within the chute and protect it from the falling material. The feed chute 21 and the castings 23 and 24 are divided horizontally at the level of the shaft 18 so that they can be assembled around the shaft and removed at any time for replacement and repair. The filler 22 is inserted in a gland ring 25 which projects into the end of the casting 14, providing a joint between the rotating casting and the stationary feed chute. Suitable packing 26 held in place by a bolted ring 27 provides an effective joint around the gland ring.

In order to prevent material from packing into the lower part of the feed chute where it enters the casting 14 it is preferred to attach to the arms or spokes 16 lifters 28 which extend into the gland ring 25 and keep the material to be ground moving freely therein. For driving purposes the shaft 18 is connected through a coupling 29 and shaft 30 to a gear box 31 containing a reduction gear, the drive for which is provided by a motor on the base. In place of a reduction gear of course any equivalent such as a reduction chain drive can be used.

The construction at the discharge end may be substantially identical with that at the feed end, the parts in question there shown in Figure 1 being numbered accordingly, but no lifter blades 28 are required, and as the dried material in this case is intended to be extracted by a current of air, the outlet consists of a casing 33 connected to an air trunk 34 which conveys the air and dried ground material to a suitable separator and fan forming no part of this invention. Air suitably heated is introduced with the material to be ground through the hopper 20. In the example of construction shown the shaft 18 is

cooled by allowing some cold air to enter through the clearance within the castings 23 and 24, the comparatively small current of cold air drawn in at this point sufficing to prevent overheating. Similar clearance is shown inside the corresponding parts 23 and 24 at the discharge end, serving a similar purpose. The shaft 18 is supported in a suitable bearing 35 and the shaft 19 in a bearing 36, the details of which form no part of the invention. They are preferably roller bearings, and one of the bearings may be mounted so as to float in its supports, thus allowing for expansion and contraction of the drum and spiders due to heating and cooling as is well known in the art.

Balls are introduced into the cylinder for grinding the material therein, the approximate level to which the balls are filled being indicated by the dotted line at 37 in Figure 1. When in operation, the balls are cascading in the cylinder and would be liable to damage the ends of the shafts 18 and 19 if they had direct access thereto. In order to prevent this, protective plates 40, which may be of cast steel say 2 inches thick, are screwed on to the projecting ends of the shafts 18 and 19 and locked by taper dowel pins 41 engaging in the hubs 17, and screwed into the ends of recesses in the caps (Figure 2). The heads of the dowel pins are thus enclosed in deep recesses, which are then filled by screwed-in plugs 41a so that the dowel pins cannot be damaged until the caps 40 are largely worn away, by which time of course they will be replaced. Any other convenient means may be adopted for securing the caps 40, but the construction shown has been found convenient.

If the mill is to be used for grinding minerals without an air current through the mill, suitable scoops or blades (not shown) similar to the lifters 28 may be provided at the delivery end for discharging material through the spider at this end to a chute (not shown) surrounding the shaft within the gland ring and sloping outwards and downwards, as is well known in the art.

When the material is airborne as described it may be delivered direct from the mill to a furnace, if the material is fuel, or to any other apparatus in which the material is to be used, or it may be delivered to a classifier to grade the material before delivery. If the material is to be separated from the air, of course it passes into a separator which may be of the "cyclone" type.

Any suitable type of balls or grinding elements may be used, whether of hard steel, metallic carbides, alumina, or ceramic materials. The

type of ball to be used depends of course on the class of material to be ground.

I claim:

- 5 1. A grinding mill comprising a cylinder containing a plurality of rolling grinding means, end members supporting said cylinder at each end thereof, each such end member comprising a spider with a hub portion and radiating arms surrounded by a coned flange portion expanding toward the interior of said cylinder, shafts supporting the hub portions of said spiders and terminating at the inner faces thereof, means for supporting said shafts outside said cylinder, said means constituting the sole supports for said cylinders, means for applying power to one of said shafts, a feed chute embracing one of said shafts, said chute forming a steeply inclined wall leading toward the spider at the feed end of the cylinder, a stationary inwardly inclined filler beneath said embraced shaft and adapted to deflect incoming material towards the cylinder, and a gland ring encircling said shaft and encompassing said filler and providing a joint between said chute and said coned flange.
- 10 2. A grinding mill as claimed in claim 1 comprising also lifters attached to the radiating arms of said spider and extending from the outer periphery thereof into the path of material delivered by said chute.
- 15 30 35
